(57) **CLAIM**

The ornamental design for a threaded spacer for tile leveling system, as shown and described.

DESCRIPTION

FIG. 1 is a perspective of a threaded spacer for a tile leveling system, with a threaded portion of the threaded spacer;

FIG. 2 is a front elevational view of the threaded spacer for tile leveling system;

FIG. 3 is a right elevational view of the threaded spacer for tile leveling system;

FIG. 4 is a top plan view of the threaded spacer for tile leveling system;

FIG. 5 is a rear elevational view of the threaded spacer for tile leveling system;

FIG. 6 is a left elevational view of the threaded spacer for tile leveling system; and,

FIG. 7 is a bottom plan view of the threaded spacer for tile leveling system.

The broken away symbols in the drawings indicate that any portion of the article beyond what is shown forms no part of the claimed design.
